UNITED STATES PATENT OFFICE.

GARRISON W. DERRYBERRY, OF SPIRO, OKLAHOMA.

ELECTRIC TRAIN-DESPATCHING SYSTEM.

1,289,695.

Specification of Letters Patent.

Patented Dec. 31, 1918.

Application filed July 8, 1914. Serial No. 849,803.

To all whom it may concern:

Be it known that I, GARRISON W. DERRYBERRY, a citizen of the United States, residing at Spiro, Le Flore county, and State of Oklahoma, have invented and discovered certain new and useful Improvements in Electric Train-Despatching Systems, of which the following is a specification.

The object of my said invention is to provide an apparatus by which all the trains to be operated on a single division of a railroad can be directed or despatched from one appropriately located office, said apparatus embodying electrically operated means by which the trains will report automatically from the various stations in the division to the train despatcher's office their respective numbers, locations and directions of travel, and electrically operated means by which the train despatcher may communicate to the engineer of any train at a station, either while standing or in motion, such orders as he may desire by means of various signals, thereby enabling the engineer to operate his train with the least possible loss of time and the greatest degree of safety and at the same time enable the train despatcher to keep advised of the exact location of every train in his division as it moves from station to station and its relative position to other trains.

Said apparatus embodies a device for verifying such orders and signals and allowing the despatcher to detect and correct any errors.

Said apparatus is also intended to reduce to a minimum the electro motive force required to operate the signal system and to minimize the time, danger, and expense attending the handling of trains, both through a central despatcher's office and various local telegraph offices, by receiving reports and giving orders direct through only one office for each division of the system.

Referring to the accompanying drawings which are made a part hereof and on which similar reference characters indicate similar parts,

Figure 1 is a diagrammatic view illustrating a section of a double track railway, including the complete apparatus as used in the train despatcher's office and at three separate stations on the division,

Fig. 2 a section through the signal box in the train despatcher's office,

Fig. 3 a top or plan view of an operating switch in the train despatcher's office for signaling to the train,

Fig. 4 a section through Fig. 3 on the dotted line 4—4, 60

Fig. 5 a sectional view through the signal box at the station,

Fig. 6 a front elevation of said signal box,

Fig. 7 a detail perspective view of a part 65 of the mechanism in said signal box,

Fig. 8 a cross section on the dotted line 8—8 in Fig. 2,

Fig. 9 a cross section on the dotted line 9—9 in Fig. 5, 70

Figs. 10, 11, and 12 detail views illustrating the construction of parts more clearly and,

Fig. 13 is a fragmentary view of the operating switch in the train despatcher's office, 75

Referring to Fig. 1, the various parts of the apparatus are arranged for a train on the track represented at the upper side of the figure to be going in one direction, and 80 a train on the track represented at the lower side of the figure to be going in the opposite direction, the respective directions of the trains being indicated by arrows.

I have represented the rails as broken to 85 indicate that the section of road represented may continue for an indefinite distance, such as might commonly include the three stations A, B, and C, as indicated on the drawing. These stations, as will be understood, 90 may be any distance apart, and different distances apart, as is common along the lines of railways. In the drawing I have illustrated, merely for convenience, the apparatus intended to be in the train despatcher's 95 office, partly on one side of the road and partly on the opposite side of the road. It will be understood, of course, that in actual practice the apparatus will be all within a single office and that the illustration is 100 merely for convenience in locating the wires so that the arrangement can be clearly seen upon the drawings.

The signal box 10, located in the train despatcher's office, contains a series of magnets corresponding to the number of stations in the division, as 11, 12, and 13, respectively, above which is formed a track 15 with two run-ways having undulations at intervals, the lowermost part of each curve 110

being at a point midway between adjacent magnets. Indicator disks, as 16 and 17 are adapted to be mounted and roll one in one run-way and the other in the other run-way of said track. Each of said indicator disks has a center or journal around which it is adapted to rotate, and tail pieces 18 and 19, respectively, are attached thereto. Said tail pieces are formed with projecting points 10 adapted to engage with a serrated upper edge 20 alongside said track, the serrations being so arranged that the points are free to drag over them in one direction, but prevent the backward movement of the disks.

15 Another series of magnets, as 111, 112 and 113, (Fig. 1) are arranged directly behind the magnets 11, 12, 13, etc., but elevated somewhat, and another undulated double track 21 is arranged immediately above them 20 on which indicator disks 22, 23, etc., are mounted in the same manner as described for those on track 15 except they are arranged to roll in the other direction. These disks have free centers with tail pieces 24 and 25 adapted to engage with a serrated top edge 26 alongside said track. The operation of these parts will be more clearly explained after the description of the construction and arrangement of the remainder 30 of the apparatus.

The indicator board 27 is of any suitable construction and has an indicator hand 28 mounted on a central pivot 29. The outer end of said hand projects over an annular groove 30 near the outer edge of said switch board. Beneath the annular groove 30 at equal distances around the switch board are mounted several pairs of magnets 31, as indicated most clearly in Figs. 3 and 4. Said board is divided into equal divisions corresponding to the number of trains in operation on the division, said divisions being indicated by the numerals 1, 2, 3, 4, 5, and 6, respectively. Each division is also 40 sub-divided into four equal divisions represented by elevations in the top edges of the walls of the groove 30. The outer end of hand 28 carries a spring detent 32 which is adapted to engage with any one of a series 45 of sockets 33 in the bottom of groove 30 and secure said hand from accidental turning on its pivot. A soft metal ball 34 is mounted on the top edges of the walls of the groove 30 and adapted to be moved step by step 50 along said groove by the magnets 31, as will be presently described.

At each station a post 35 is located alongside the track, on the top of which is mounted a terminal contact member 36. A rotary 60 arm 37 is mounted on a vertical pivot pin 38 on the top of said post, said arm being mounted on a ratchet wheel 39 and extending outwardly from diametrically opposite sides thereof. Said pivot pin 38 is fixed in 65 the top of said post and on its outer end car-

ries a lever 40 having a pawl 41 which engages with the teeth of said ratchet wheel 39. Said pawl normally stands in the position shown in Fig. 11 with its position determined by a stop pin 42 properly located 70 in the top of said post. A spring 43 connected at one end to said pin 38 and at the other end to said lever 40, tends to hold said lever against said pin 42 and return it to said position when it is forcibly operated 75 away therefrom. A spring bumper 143 is located on the opposite side of said post to limit the movement of lever 40 in that direction.

The station signal box 44 contains an indicator wheel 45 on the periphery of which is formed a series of numerals indicating the number of the trains corresponding to the number of divisions on indicator board 27, and these numerals are adapted to show 80 through an opening 46 in the end of said box. (See Fig. 6). Said indicator wheel is mounted on a shaft 47 journaled in the sides of said box 44. A wheel 48 with horizontal pins *p* projecting from one side of 85 its rim, which serve as cogs, is made fast to wheel 45. Its pins engage a cog wheel 49 on a short shaft 50. Said shaft 50 is journaled at its outer end in a bearing in one end of box 44 and at its inner end in 90 a suitable support 51. On its outer end it carries an indicator arm 52 as will be presently described. Said wheel 48 is normally operated by a spring 53 connected at one end to shaft 47 and at its other end to 95 said wheel. Said shaft has a bevel pinion 54 on one end which meshes with a similar pinion 55 on a shaft 56 by which said spring is kept wound up under operative tension in a manner which will be presently 100 described. A magnet 57 is positioned adjacent to said wheel, and a double-ended pawl 58 is pivoted at 59, which carries an armature 60. Said pawl is adapted to be operated in one direction by said magnet and in 105 the other direction by spring 160. The opposite points of the pawl 58 are adapted 110 to engage alternately with the cogs or pins of the wheel 48 and operate in the same manner as a clock escapement mechanism. Another similar pawl 61 is pivoted at 62 and has a spring arm 63 which engages with a notch in the periphery of a wheel 64, which is pivoted at 164. Said wheel is connected 115 in one side of the main electric circuit and 120 has an arm 65 which is adapted to contact with a terminal 66 connected with the other side of the circuit, whereby the rocking of said wheel is adapted to make and break said circuit. A wire 67 leads from the 125 wheel 64 to a contact plate 68 below the box 44. A wire 69 leads from the contact terminal 66 to one end of the coil of magnet 57, and another wire 70 leads from the 130 opposite end of said coil to the ground. An-

other contact plate 71 is arranged adjacent to contact plate 68, a space being provided between them and a wire 72 leads from said contact plate 71 by appropriate connections 5 to the office of the train despatcher. A tilting arm 73 is pivoted at 74 on the end of contact plate 71 and has a branch extending beyond its pivot within the field of a magnet 75, for a purpose to be presently described.

On the lower end of shaft 56 is mounted a wheel 76, the rim of which is formed, for one fourth of its circumference, on diametrically opposite sides, of a width to bridge 15 the space between contact plates 68 and 71. The other portions of the wheel are narrow so that they will pass between said contact plates without bridging said space. The thickened portions of wheel 76 are indicated 20 by the numeral 77 and the thin portions by the numeral 78.

Wire 72 leads from contact plate 71 by appropriate connections to the office and may be connected through connections 105 25 and 106 by branches 84 to the windings of magnets 31, which windings run from said magnets, as by branches 83, to the metallic sections of the inner wall 79 of the groove 30 in the indicator board 27. Wall 79 of 30 said groove 30 is formed of alternate sections of insulating material and metal, the metal sections of wall 79 being connected with the windings of the magnets 31, as above stated. The wall 80 is a continuous 35 metal wall and is connected by branch wires 81 with a ground wire as 99. The diameter of ball 34 is slightly greater than the width of groove 30 so that it will roll freely on the track formed by the top edges of walls 40 79 and 80. It thus contacts with both walls and is adapted to form an electrical bridge or connection between them. The bottom of groove 30 may be of any suitable material, of appropriate thickness, and the insulated sections of the wall 79 are arranged 45 adjacent to each set of magnets. Said sections are indicated by numeral 85. When the ball is released from the magnetic influence of the magnets, when positioned 50 above them, it will thus be free to roll away from one set of said magnets and toward the next set.

The construction and arrangement of the parts having been thus described, the invention will be better understood from a description of the use and operation of the apparatus, which is as follows:

The parts of the apparatus being arranged as illustrated in Fig. 1, and the train 60 approaching station B from station C on the track at the upper side of said figure, a contact arm on the side of the locomotive (not shown) will strike lever 40 which will be thrown against spring bumper 143 on the 65 opposite side of the post, and, through the

connection of the pawl 41, will turn ratchet wheel 39 to bring contact arm 37 in contact with contact point 36, thus closing the circuit through wire 90, local battery 91, the winding of magnet 75, and ground wire 92, 70 energizing said magnet 75 which will attract the lower end of the pivoted bridge piece 73 and send the current from battery 95 through the circuit formed by the wire 70, magnets 57, wires 69, 67, 72, 96, 196, magnet 75 12, wires 97, 98, 99 and 100, to the ground. The closing of this circuit energizes magnet 12 and draws the indicator disk, such as 16, (located in the same relation to magnet 12, as shown at the left in Fig. 2, as the relation 80 between magnet 11 and indicator 16), representing the number of the train, as No. 5, to the position on said track immediately above said magnet 12. Said indicator is held above magnet 12 by a sliding finger 15 on 85 the inner end of the pivoted lever 120 (see Fig. 8) until manually released. Magnet 12, representing station B, and being indicated by the same name or number as the station, will show the train despatcher that 90 the train indicated by the number of the disk has passed the point at which the post 35 is located and is approaching the station. The distance of the post from the station is fixed as may be 95 desired so that the train despatcher will have the opportunity that may be required to indicate to the engineer any instructions which may be conveyed through the medium of the signal box 44 and the signaling apparatus 100 therein.

A contact arm (not shown) is also provided on the rear end of the train so that as the rear end passes post 35 lever 40 will be thrown another quarter turn which will turn 105 arm 37 to the position shown in station A and disconnect said arm from the contact 36. The pivoted bridge piece 73 will stand in position, however, to maintain the circuit until the contact arm on the locomotive 110 strikes arm 130 which is connected with the wheel 76 in the same manner that lever 40 is connected with the arm 37. The turning of said wheel throws pivoted bridge piece 73 back on its pivot and brings the wide portion 77 of said wheel between plates 68 and 71, thus maintaining the circuit. When the rear end of the train passes station B the contact arm thereon will strike lever 130 and turn said wheel to bring a thin portion 78 120 thereof between contact plates 68 and 71, breaking the main circuit and allowing the indicator disk 16 (or the one in use) to roll from the position above the magnet 12 which has been holding it and allow it to roll toward the next magnet, which indicates to the train dispatcher that the train has left station B and is approaching toward the next station, or station A in the operation being described.

This operation continues throughout the division and from one division to another throughout the entire system.

The circuit from battery 95 being closed, 5 as before described, the indicator disk is drawn to above magnet 12 by magnetic force, as above described, and is there held, even after the circuit is broken, through the medium of one of the vertical sliding fingers 10 121 on the inner end of one of the pivoted bars 120 which normally projects upward in front of said disk 16 (or any other disk that may be in use), thus holding said disk from rolling downwardly on the inclined 15 surface of the track 15 until said finger is moved out of the path of said disk, as will be presently described. The train despatcher then breaks the circuit through magnet 12 by removing plug 101, connected with the 20 end of wire 96, from a socket forming the terminal of wire 196 and inserts said plug in a socket of a terminal 102 which terminal is connected by a wire 103 through a local battery 104, from which another wire 105 runs to a terminal 106 on indicator board 27 25 from which branches 84 run to magnets 31 and metallic sections of wall 79 of groove 30. Terminal 107 is connected with wall 80, and by wires 99 and 100, through battery 95, to 30 the ground.

It will thus be seen that by removing the plug from the socket in terminal 101 and inserting it in the socket in terminal 102, said magnet 12 is deenergized and the electrical circuit is connected through the indicator board 27, and also through the circuit operating the signaling apparatus in signal box 44. The despatcher, through the medium of lever 28 is thus enabled to operate 40 the signaling apparatus in box 44 to indicate various signals at the station B to which the train is approaching in the following manner: For example, suppose the hand 28 is in the position indicated in Fig. 45 3, the apparatus in signal box 44 will be operated to show the signal No. 5 on the periphery of wheel 45 through the opening 46 in the end of box 44 and the arm 52 will stand horizontally covering the red arm 155 50 and indicating to the engineer that he has a clear track and can proceed. If the train despatcher desires the engineer to stop at station B he will leave the hand 28 standing in its normal position between the divisions 55 1 and 6 on the indicator board, in which position the periphery of the indicator wheel 45 shows a plain red section through the opening 46, the indicator arm 52 stands in the position shown in whole lines in Fig. 60 6, (likewise its normal position), and the red arm 155 is exposed. This indicates to the engineer to stop. If the train despatcher wishes the engineer to know that another train is following, he moves the arm 28 to 65 position 125 when signal arm 52 will stand

at an angle in relation to arm 155. If he wishes the engineer to know that there is another train ahead he will remove the hand to position 126 which will move indicator arm 52 to stand at another angle in relation 70 to arm 155. When the despatcher wishes to signal the engineer to proceed, he moves indicator hand 28 around to the number indicating the number of the train which brings the number of the train in view through the 75 opening 46 and brings white indicator arm 52 longitudinally of the red arm 155, covering said arm and indicating to the engineer that the track is clear and he may proceed. 80

This operation proceeds through the action of the electric current in energizing the magnet 57 which overcomes the power of spring 160, draws the armature 60 to the poles of the magnet, releases wheel 48 and permits spring 53 to turn said wheel one step which operates lever 61 to rock wheel 64 to break the connection between terminal 66 and arm 65, deenergizing magnet 57 and permitting spring 160 to throw pawl 58 90 back, thus turning wheel 48 the space of two of its pins or cogs and operating shaft 50 and indicator arm 52 correspondingly. The ball 34 is operated to follow hand 28 by means of the successive energizing of 95 the magnets 31 as follows: The current coming through wire 72 and connection 105 to terminal 106, which is electrically connected with each of the metallic sections of the wall 79, the circuit is completed through 100 the successive sections by the metallic ball 34 as it rolls from one section to the other. For example, the ball standing in the position shown in Fig. 3 is directly above one pair of magnets 31. When the hand 28 is 105 moved from this position, said ball will roll down over the inclined section of track toward the next set of magnets 31, rolling off the insulated section 85 and establishing an electric circuit from wire 72 through the 110 next set of magnets to the ground, thus energizing said magnets and drawing said ball up over the elevation adjacent thereto, the magnetic force of the magnets holds the ball until the circuit is broken when it rolls 115 down toward the next set of magnets and the operation continues until the ball is stopped by the locked position of the hand 28 with which it contacts.

Thus the breaking and making of the circuit by the operation of the pawl 61 causes the indicator devices, consisting of the indicator wheel 45, and the hand 52, to be operated to indicate the various code of signals determined by the relative position of the 125 arm 52 and the arm 155 and the signaling numbers or colors on the periphery of wheel 45.

In the operation of the apparatus by the despatcher the indicator disks 16, 17, 22, 130

and 23, for example, are arranged convenient to the indicator box 10 and when, according to the schedule, a train is due to enter the division under the control of the 5 train despatcher, he selects the indicator disk bearing the number corresponding to the number of the train and places it upon track 15 or 21, according to whichever direction the train is going, near the magnet 10 representing the station which the train will first approach. As soon as the train passes the outpost 35 near said station the despatcher is automatically informed of the fact and then manipulates his switches 101 15 and 28 to operate the signal at said station and communicate to the engineer the information desired. The operation continues in the same manner throughout the division, the indicator moving from station 20 to station as the train continues on its way and when it passes from the division controlled by the office, the disk indicator leaves the end of the track and falls into a receptacle (not shown) arranged to receive 25 the disks. The train despatcher of one division is, of course, in communication with the despatchers of the divisions on each side of his division and communicates with them and they communicate with him as to the 30 passing of the trains from one division to the next. This communication can be carried on by telegraph, or by telephone, in the usual way.

Having thus fully described my said invention, what I claim as new and desire to secure by Letters Patent is:

1. An electrically operated train despatching system comprising an indicator mechanism in the train despatcher's office, 40 signaling mechanism at each station under the control of the train despatcher's office, a circuit connecting said mechanisms, means for breaking and making said circuit by the train in passing the station, and means in the train despatcher's office for operating 45 the signaling mechanism at any station on the circuit to signal the passing trains as may be desired, substantially as set forth.

2. An electrically operated train despatching apparatus comprising an indicator mechanism in the train despatcher's office, a signaling mechanism at each station in the division, said several signaling mechanisms and the indicator mechanism being connected in a common electric circuit, means operated by the passing train for closing the circuit as it approaches each station and opening the circuit as it leaves each station, the indicator mechanism in the train despatcher's office being arranged to be operated by the closing of the circuit to indicate to the despatcher the approach of the train to any station, and signal operating means in the train despatcher's office for operating 65 the signaling mechanism at the station,

whereby it is possible for the train despatcher in his office to signal orders to the train at a station, substantially as set forth.

3. An electrically operated train despatching apparatus comprising indicator 70 mechanism in the train despatcher's office, signaling mechanism at each station in the division under control of said office, an electric circuit connecting the signaling mechanism at the station with the indicating 75 mechanism at said office, signal operating means also in the train despatcher's office and connected in said circuit, a connection whereby the train is adapted to close the circuit as it approaches the station and operate 80 the indicator mechanism in the office and open the circuit as it leaves the station, and a station signal operating apparatus in the office connected in the same circuit and arranged to operate the signal at the station to 85 indicate the orders to the train, substantially as set forth.

4. An electrically operated train despatching system comprising an indicator mechanism in the train despatcher's office containing 90 a series of magnets corresponding in number to the number of stations in the division, indicator devices adapted to be operated by said magnets as the train moves from station to station, means for holding 95 said devices at each magnet after the magnet is deenergized, a signaling apparatus at each station, an electric circuit connecting the signaling apparatus of each station with the magnet representing said station 100 in the indicator mechanism in the train despatcher's office, a controller in the train despatcher's office for controlling the signaling apparatus at each station, a switch for connecting said controller into the circuit with 105 said signaling apparatus, and means for closing the circuit and energizing the magnet in the indicator mechanism in the train despatcher's office by the approach of the train to the station, and means for opening 110 said circuit by the departure of the trains, substantially as set forth.

5. An electrically operated train despatching system comprising an indicating apparatus in the train despatcher's office containing 115 a series of magnets corresponding with the number of stations in the division for each direction of movement on the track, said indicator apparatus comprising an indicator device arranged to be operated step 120 by step from one magnet to the next as the train moves from one station to the next, a signal at each station adapted to signal to the engineers of trains such orders as the train despatcher in the office may desire to 125 give, a controller in the train despatcher's office arranged to operate said signal to indicate a variety of orders at will, an electric circuit connecting each station signal with the appropriate magnet in the indicator in 130

the train despatcher's office, a switch arranged to connect the controller at will in any circuit, and means for closing and opening the circuit at the station by the approach and departure of the train, whereby the train despatcher on the approach of any train to any station as indicated on the indicator is able through the controller to signal to such station such orders as he may desire, substantially as set forth.

6. An electrically operated train despatching system comprising an indicator in the train despatcher's office arranged to indicate the position of the trains throughout the division, a signal at each station for signaling orders from the train despatcher's office, a controller in the train despatcher's office,

an electric circuit connecting each station signal with the indicator in the train despatcher's office, means for closing and opening the circuit at the station, means for locking the indicator temporarily, and a switch for connecting the circuit from each station successively through the controller, substantially as set forth.

25

In witness whereof, I have hereunto set my hand and seal at Washington, District of Columbia, this ninth day of May, A. D. nineteen hundred and fourteen.
